(57) **CLAIM**

The ornamental design for a vacuum sealing packaging machine, as shown and described.

DESCRIPTION

FIG. 1 is a front, left and top perspective view of a vacuum sealing packaging machine, showing my new design;

FIG. 2 is a rear, right and bottom perspective view thereof;

FIG. 3 is a front view thereof;

FIG. 4 is a rear view thereof;

FIG. 5 is an enlarged left side view thereof;

FIG. 6 is an enlarged right side view thereof;

FIG. 7 is a top plan view thereof;

FIG. 8 is a bottom plan view thereof; and,

FIG. 9 is a front perspective view shown in an open state thereof.

The broken lines shown in the drawings illustrate portions of the vacuum sealing packaging machine that form no part of the claimed design.
